UNITED STATES PATENT OFFICE.

GEDEON BOISSONNEAULT AND NAPOLEON BOISSONNEAULT, OF MANCHESTER, NEW HAMPSHIRE.

BOBBIN-HOLDER.

No. 884,366.

Specification of Letters Patent.

Patented April 14, 1908.

Application filed November 16, 1907. Serial No. 402,364.

To all whom it may concern:

Be it known that we, GEDEON BOISSONNEAULT and NAPOLEON BOISSONNEAULT, citizens of the United States, residing at 5 Manchester, in the county of Hillsboro and State of New Hampshire, have invented new and useful Improvements in Bobbin-Holders, of which the following is a specification.

Our invention relates to means for holding 10 bobbins or filling carriers in shuttle bodies; and it contemplates the provision of a simple and inexpensive device for the purpose stated, constructed with a view of facilitating the positioning of a bobbin in the device when 15 the bobbin is placed in the shuttle body.

The invention will be fully understood from the following description and claims when the same are read in connection with the drawings, accompanying and forming 20 part of this specification, in which:

Figure 1 is a detail plan view illustrating portions of a shuttle body and a bobbin in dotted lines and our novel holder in full lines as properly arranged relative to the shuttle body and the bobbin to hold the latter in the former. Fig. 2 is a longitudinal vertical section of the holder as the same appears when removed from the shuttle body. Fig. 3 is a transverse section taken in the plane indicated by the line 3—3 of Fig. 2, looking in the direction of the arrow, and Fig. 4 is a detail view showing the spring and the roller therein.

Similar letters designate corresponding parts in all of the views of the drawings, referring to which:

A is a shuttle body.

B is a bobbin or filling carrier properly arranged in and relative to the shuttle body.

C is the body of our novel holder for securing the bobbin in working position in the shuttle body, and D is the spring of the holder. The body C is formed of one piece of steel or other metal compatible with its function; and it comprises a shank a adapted 45 to be fixed in the shuttle body A, and open jaws b diverging in a curvilinear manner from the inner end of the shank a. These jaws b are provided in the inner sides of their forward portions with vertical or approximately vertical grooves c shaped to form inclined holding surfaces d for engaging the circumferential projections e on the bobbin B and holding said bobbin in proper position in the shuttle body A; and said jaws b are also 55 provided in their inner sides with grooves f

which communicate with and extend outward and upward, preferably at an obtuse angle as shown, from the upper ends of the grooves c. The said grooves f, in the preferred embodiment of our invention, are preferably of concave form in cross-section, and they serve to guide the circumferential projections e on the bobbin into the grooves c and also serve to prevent the bobbin flying out of the holder.

The spring D is provided on its inner portion with an inclined stretch g, and in the lower and inner portion of said stretch is formed an opening h in which is disposed a roller E which projects slightly beyond the face of the said stretch g as shown for a purpose which will be presently pointed out in detail. The said roller E is loosely mounted on a transverse pin F so as to assure its turning freely in the opening h, and the said pin F is carried through ears i bent upwards from the base of the spring, and its ends are upset against the outer sides of the said ears or are otherwise fixed thereto in any manner suitable to the purpose of the holder.

It is necessary in placing the bobbin in our novel holder, to hold the bobbin at such an angle of inclination as to aline its projections e with the grooves f, and then move the said projections e through the grooves f and into the grooves c. Incident to this operation the roller E serves to force the bobbin to slide in the grooves f and seat in the grooves c, and it also serves when the bobbin is in proper working position in the shuttle body, 90 to exert pressure against the base of the bobbin and assist in the proper retention of the bobbin in the holder. Because of this and the fact that the bobbin must assume an inclined position before it can leave the holder, 95 there is no liability of the bobbin flying out of its proper position in the shuttle body.

As will be gathered from the foregoing, the roller E contributes to the efficiency of bobbin holders of the type illustrated and described, and yet does not appreciably add to the cost of producing the same.

Having described our invention, what we claim and desire to secure by Letters-Patent, is:

1. A bobbin holder for use in a shuttle body, comprising a body having open jaws in the inner sides of which are upright grooves and inclined grooves communicating with and extending at an angle from the upper 110

- ends of the upright grooves, and a roller mounted between the outer portions of the open jaws.
2. A bobbin holder for use in a shuttle body, comprising a body having open jaws in the inner sides of which are grooves, and a roller mounted between the outer portions of the open jaws.
3. A bobbin holder for use in a shuttle body, comprising a body having open jaws in the inner sides of which are upright grooves and inclined grooves communicating with and extending at an angle from the upper ends of the upright grooves, a device carried by the body and having an inner portion inclined parallel to the upper grooves and provided with an opening, and a roller mounted in the device and extending through the said opening in the inclined portion of the device.
4. A bobbin holder for use in a shuttle body, comprising a body having open jaws in the inner sides of which are upright grooves and inclined grooves communicating with and extending at an angle from the upper ends of the upright grooves; said body also having a shank, a spring straddling the shank of the body and having an inner portion inclined parallel to the upper grooves and provided with an opening, and also having a base and ears extending upward therefrom at opposite sides of the inclined por-
- tion, a transverse pin extending between and fixed to the said ears of the spring, and a roller mounted on said pin and extending through the opening in the inclined portion 35 of the spring.
5. The combination of a device adapted for use in a bobbin holder and having a forward inclined portion, and a roller mounted in and carried by said device and projecting 40 beyond the face of the inclined portion thereof.
6. The combination of a spring designed for use in a bobbin holder and having an upper portion, an inclined forward portion in 45 which is an opening, a base portion, and ears extending upward from the base portion and disposed at opposite sides of the inclined portion, a transverse pin secured in said ears of the spring, and a roller mounted on said 50 pin and projecting through the opening in the inclined forward portion of the spring.

In testimony whereof we have hereunto set our hands in presence of two subscribing witnesses.

GEDEON ^{bis} X BOISSONNEAULT.
